UNITED STATES PATENT OFFICE.

LAWRENCE KIELB, OF ORLEANS, MINNESOTA.

COMBINED COMB AND BRUSH.

1,274,720.

Specification of Letters Patent. Patented Aug. 6, 1918.

Application filed March 4, 1918. Serial No. 220,304.

To all whom it may concern:

Be it known that I, LAWRENCE KIELB, a citizen of the United States of America, residing at Orleans, in the county of Kittson 5 and State of Minnesota, have invented certain new and useful Improvements in Combined Combs and Brushes, of which the following is a specification.

The primary object of the invention is the 10 provision of a serviceable hair-combing device compactly arranged upon a hair-brush ready for immediate use when desired.

A further object of the invention is the 15 provision of a folding comb provided for a hair-brush adapted for compact arrangement thereon and readily locked as well as released when in either its folded or unfolded position, the structure being easy and inexpensive to manufacture.

20 A still further object of the device is the provision of a foldable comb structure arranged with a serviceable locking means and being in the nature of an attachment readily assembled with a desirable portion 25 of the brush during the manufacture thereof and possessing great strength and utility.

In the drawing:—

Figure 1 is an elevational view of a brush-handle provided with my device illustrated 30 in its folded position, the cover-plate being removed;

Fig. 2 is a similar view illustrating the comb in its open operative position;

Fig. 3 is a side elevation of the complete 35 brush-handle with the comb open;

Fig. 4 is an elevational view thereof with the comb closed; and

Fig. 5 is a perspective view of the comb-locking latch.

40 While it will be understood that my foldable comb may be arranged in any member where the same would be desirable for use, such as a hand mirror or brush, the same is herein illustrated and arranged within the handle 10 of a brush 11 having the usual back 12 for supporting the bristles 13.

The handle 10 is arranged with a chamber 14 therein in the nature of a slot opening as at 15 in one side edge 16 of the handle 10 and 50 preferably having a cover-plate 17 normally overlying the chamber 14 and forming a part of the said handle. A comb 18 is pivoted at one end within the chamber 14 by means of a transverse pin 19, whereby the comb may 55 swing inwardly of the slot 15 to its folded arrangement as shown in Fig. 1 of the draw-

ing while the comb may also be swung outwardly in longitudinal arrangement with respect to the brush 11 with the back 20 of the comb engaging a shoulder 21 at the outer end 60 of the chamber 14 and at the free end of the handle 10 and acting as a positioning means for the comb when in its operative position ready for use.

A U-shaped locking latch 22 is slidably 65 mounted within the chamber 14 having a bolt 23 and one end thereof mounted upon a resilient portion 24 of the back of the latch while a locking hook 25 is arranged at the opposite end of the latch upon a solid portion 26 of the back thereof. The solid portion 26 is slidably arranged against the inner wall 27 of the chamber 14 when the device is assembled with a fixed guard 28 arranged at the opposite side of the back of 75 the latch and whereby the latch is positioned longitudinally slidable within the chamber 14.

A keeper-notch 29 is provided in the free end of the comb 18 adapted for receiving the locking end 30 of the hook 25 when the comb is positioned within the chamber 14. A plurality of springs 31 are carried by the inner wall 32 of the chamber 14 bearing upon the hook 25 normally forcing the same inwardly 85 and tending to seat the hook end 30 within the notch 29.

The bolt 23 and latch portion 24 are capable of shifting by reason of an extension or offset 23 of the chamber 14 and whereby the bolt 23 may seat within opposite notches 34 and 35 when the comb is in its closed or open arrangement respectively.

A leaf-spring 36 is carried by the guard 95 28 for engaging the comb 18 and cushioning the inward movement thereof when the comb is closed while it will be also evident that upon releasing the comb the spring 36 will assist in swinging the comb to its open position. A release rod 37 is carried by the bolt 100 23 projecting through an angular slot 38 in the cover-plate 17 and provided with a finger-engaging plate 39 upon its outer end.

When the comb 18 is open, as shown in Fig. 2 of the drawing, the rod 37 may be 105 moved for releasing the bolt 23 from the notch 35 of the comb and whereupon the comb may be readily swung to its closed position within the handle 10 through the slot 15 and compressing the spring 36. During 110 this movement of the comb, the bolt 23 resiliently engages the curved end 40 of the

comb and will automatically seat within the notch 34 when the comb is closed. The inclined free end 41 of the comb engages the hook end 30 prior to this engagement of the bolt 23 with the comb notch 34 and will longitudinally move the latch 22 permitting the free end of the comb to enter the chamber 14 and whereupon the latch end 30 will seat within the latch 29 at the free end of the 10 comb.

When it is desired to open the comb 18, the rod 37 will be moved into the inner end 42 of the slot 38, it being necessary to move the rod 37 through both portions of the said 15 slot 38 to reach the inner end of the slot and which movements it will be apparent will first swing the bolt 23 inwardly releasing the bolt from the comb and will then move the latch 22 longitudinally releasing the 20 hook end 30 from the notch 29 so as to permit the spring 36 to swing the comb 18 to its open position. A positioning pin 43 is transversely arranged through the chamber 14 extending through a slot 44 in the back 25 portion 26 of the latch 22 for limiting the longitudinal movement of the latch.

A serviceable comb attachment for brush-handles is provided in which the comb will not interfere with the use of the brush when 30 the comb is in either its open or folded position, the comb being readily shifted to the opposite extremes of its swinging movement and automatically locked in such positions when the same have been reached.

35 What I claim as new is:—

1. In combination with a handle having a chamber, a comb pivoted at one end within the chamber adapted for swinging outwardly thereof in its operative position, a 40 locking latch for the comb longitudinally shiftably arranged within the chamber, resilient positioning means for the latch, one portion of the latch being resilient and provided with a bolt adapted for engaging the 45 comb adjacent the pivoted end thereof, and releasing means for the latch carried by said bolt adapted for flexing the resilient portion of the latch during the retracting of the bolt.

50 2. In combination with a handle having a chamber, a comb pivoted at one end within the chamber adapted for swinging outwardly thereof in its operative position, a locking latch for the comb longitudinally shiftably 55 arranged within the chamber, resilient positioning means for the latch, one portion of the latch being resilient and provided with a bolt adapted for engaging the comb adjacent the pivoted end thereof, releasing means 60 for the latch carried by said bolt adapted for flexing the resilient portion of the latch during the retracting of the bolt, the opposite end of the latch being arranged with a hook adapted for engaging the free end of 65 the comb when the latter is in its folded po-

sition, the said releasing means being further adapted for longitudinally moving the latch and disengaging the hook after the releasing of the said bolt.

3. A device of the class described comprising a brush-handle having a side-opening chamber therein, a comb pivoted at one end within the chamber adapted for swinging movement inwardly and outwardly of the chamber, a latch longitudinally movable within the chamber having a resilient end portion adapted for lateral movement therein, a locking bolt upon the resilient end of the latch adapted for engaging the pivoted end of the comb when in either its 70 open or closed arrangement, and a hook at the opposite end of the latch adapted for locking engagement with the free end of the comb when the latter is closed within the handle. 75

4. A device of the class described comprising a brush-handle having a side-opening chamber therein, a comb pivoted at one end within the chamber adapted for swinging movement inwardly and outwardly of the chamber, a latch longitudinally movable within the chamber having a resilient end portion adapted for lateral movement therein, a locking bolt upon the resilient end of the latch adapted for engaging the pivoted 90 end of the comb when in either its open or closed arrangement, a hook at the opposite end of the latch adapted for locking engagement with the free end of the comb when the latter is closed within the handle, a 95 guard within the chamber adjacent the latch, an automatic opening spring for the comb carried by said guard, and resilient normal positioning means for the latch arranged adjacent the hook. 100

5. A device of the class described comprising a brush-handle having a side-opening chamber therein, a comb pivoted at one end within the chamber adapted for swinging movement inwardly and outwardly of the chamber, a latch longitudinally movable within the chamber having a resilient end portion adapted for lateral movement therein, a locking bolt upon the resilient end of the latch adapted for engaging the pivoted 110 end of the comb when in either its open or closed arrangement, a hook at the opposite end of the latch adapted for locking engagement with the free end of the comb when the latter is closed within the handle, the said handle having an angular slot through one side thereof, an operating rod for the latch carried by the latch-bolt and projecting through said slot, and a finger-engaging plate upon the outer end of said 115 rod. 120

6. A device of the class described comprising a brush-handle having a side-opening chamber therein, a comb pivoted at one end within the chamber adapted for swing- 125 130

ing movement inwardly and outwardly of the chamber, a latch longitudinally movable within the chamber having a resilient end portion adapted for lateral movement therein, a locking bolt upon the resilient end of the latch adapted for engaging the pivoted end of the comb when in either its open or closed arrangement, a hook at the opposite end of the latch adapted for locking engagement with the free end of the comb when the latter is closed within the handle, a guard within the chamber adjacent the

latch, an automatic opening spring for the comb carried by said guard, resilient normal positioning means for the latch arranged adjacent the hook, the said handle having an angular slot through one side thereof, an operating rod for the latch carried by the latch-bolt and projecting through said slot, and a finger-engaging plate upon 15 the outer end of said rod.

In testimony whereof I affix my signature.

LAWRENCE KIELB.
